F. W. Warner
Morrer.

N° 29425

Patented Jul. 31, 1860

UNITED STATES PATENT OFFICE.

FREDK. W. WARNER, OF EAST HADDAM, CONNECTICUT.

IMPROVEMENT IN MOWING-MACHINES.

Specification forming part of Letters Patent No. 29,425, dated July 31, 1860.

To all whom it may concern:

Be it known that I, FREDERICK W. WARNER, of East Haddam, county of Middlesex, and State of Connecticut, have invented certain new and useful Improvements in Mowing-Machines; and I do hereby declare that the same is described and represented in the following specification and drawing.

To enable others skilled in the art to make and use my improvement, I will proceed to describe its construction and operation, referring to the drawing.

My invention relates to an improved construction and arrangement of the main frame which carries the gearing in relation to the draft-frame, driver's seat, and cutting apparatus, as hereinafter fully described.

In the accompanying drawing is shown an isometrical view representing the parts partly by red or dotted lines.

A is the master-wheel, having an internal gear which operates the machine.

B is the shaft or axle, to which the master-wheel is secured, and upon or by which all of the other parts are supported.

A' is a wheel upon the outer end of the shaft B to support and balance the operating parts.

C are the thills by which the machine is drawn.

D is the frame-work, (to which the several parts of the machine are attached,) secured loosely to the shaft B.

E is a short horizontal shaft secured to the upper portion of the frame-work, having a pinion-gear, F, secured on the inner end in such a manner as to allow it to mesh into the internal gear of the master-wheel A. Upon the other end is secured a bevel-gear wheel, G.

H is an upright shaft having a small bevel-wheel, I, which meshes into and is operated

upon by the gear G. On the lower end of said shaft is secured a crank-wheel, J.

K is the cutter-case, secured diagonally to the frame-work D. The fingers are made in the usual way.

L is the cutter-blade, secured to two parallel arms, P, which are of equal length and secured to the case the same distance apart as they are on the blade, so as to produce an equal motion of the blade.

M is a connecting-arm from the blade L to the pin in the crank-wheel.

N is the operator's seat, secured to the thills C.

O is a foot-piece (being a portion of the frame-work) extending forward of the shaft B, so that the operator may keep one foot thereon, and thereby lift the case from the ground or over any obstacle which may be in the way. The cover or lid of the case is removed to show more clearly the construction and arrangement.

I believe I have thus described my improvement so as to enable a person skilled to make and use the same; and also that the advantage to be derived in its use will be understood therefrom.

I do not claim the device as described in a Patent No. 13,285, dated July 17, 1855.

I claim—

The combination of the frame extending in front of the main axle with the draft-frame or thills, driver's seat, and cutting apparatus, the front end of frame D serving as a treadle to elevate the cutting apparatus, and the several parts being constructed and arranged in the manner described.

FREDERICK W. WARNER.
